[57] CLAIM

The ornamental design for an I.V. infusion pump, substantially as shown.

DESCRIPTION

FIG. 1 is a perspective view of an I.V. infusion pump, showing our new design;

FIG. 2 is a front elevational view of the I.V. infusion pump;

FIG. 3 is a right side view of the I.V. infusion pump;

FIG. 4 is a back view of the I.V. infusion pump;

FIG. 5 is a bottom view of the I.V. infusion pump; and

FIG. 6 is a perspective view of the I.V. infusion pump

as seen in FIG. 1 with the door open.
